UNITED STATES PATENT OFFICE.

JAMES C. SCOTT, OF MANCHESTER, COUNTY OF LANCASTER, GREAT BRITAIN.

DIVIDING-ENGINE.

SPECIFICATION forming part of Letters Patent No. 247,853, dated October 4, 1881.

Application filed January 28, 1881. (No model.) Patented in England March 15, 1878.

To all whom it may concern:

Be it known that I, JAMES CUTHBERT SCOTT, of Manchester, in the county of Lancaster, Great Britain, have invented new and useful Improvements in Apparatus for Setting Out, Marking, or Cutting Divisions of Circles or Straight Lines, of which the following is a specification.

My invention consists in an arrangement whereby I am enabled to dispense with change-wheels, and to secure an increased accuracy of division. To accomplish this I cause the handle which gives motion to the movable part always to start from the same point and to finish after the required number of turns and fraction of a turn against an adjustable stop on a graduated disk, after which it is turned in the reverse direction back to the starting-point.

In the accompanying drawings, Figure 1 is a plan view of the apparatus, partly in section. Fig. 2 is another plan view, not in section, and omitting a portion of Fig. 1; and Fig. 3 a face view of Fig. 2.

Similar letters of reference indicate corresponding parts.

At *a* is a fixed bearing, which may be attached to any suitable frame of the machine to which the dividing apparatus is to be applied. This bearing is formed hollow, and through it there passes a shaft, *b*, one end of which is provided with a worm, *c*, in gear with a wheel, *d*, which is mounted so as to be capable of turning upon a center, *e*. Upon the other end of the axis *b* is mounted loosely a handle, *f*, but it is capable of being made fast with the shaft *b* by means of a clamp, *g*, and in the following manner:

The handle *f* extends from an arm, *h*, which is provided with two jaws, *i* *i*, which embrace the shaft *b*, and these jaws are capable of being tightened on the shaft *b* by means of a handle, *k*, which carries a screw, *l*, working in the said jaws *i*.

From the arm *h* extends a boss, *m*, and upon an extension, *a'*, of the bearing *a* there is a disk, *nn'*, mounted loosely, but capable of being made fast with the said part *a'* by means of a thumb-screw, *o*. The said disk is formed with a circular slot, *p*, within which is adapted a stop, *q*, capable of being fixed in any position around the circle by means of a set-screw, *r*, and the

face *q'* of this stop may therefore be made to represent any one of the divisions marked upon the periphery of the disk *n'*, as shown in Fig. 2. These divisions, however, are only partially shown; but they extend around the entire circumference of the disk.

The handle *f* is provided with a groove, *s*, within which is situate a trigger, *t* *t'*, capable of turning upon a center, *u*, the part *t'* being forced inward by a spring, *v*, carried by the groove of the said handle, and when so forced inward it takes into a notch, *w*, formed on the edge of the disk *n'*.

The operation is as follows: The attendant, by tightening the clamp *i* *g*, makes the handle *f* fast with the shaft *b*, and the stop *q* is adjusted, so that when the trigger *t'* arrives in contact therewith the trigger will be forced by the spring *v* into the notch *w*, and thus the starting-point, which is constant, is attained. Suppose, now, that an entire revolution of the handle *f* is desired, the trigger *t'* is moved from the notch *w* by pressing the part *t* against the force of the spring *v*, and the said revolution is performed, the stop *q* being turned upward upon a center to admit of the said entire revolution, after which the trigger *t'* again passes into the notch *w*, and so on for any required number of whole revolutions. Supposing, now, however, that, say, three and a portion only of fourth turn are required, then the calculation is made in the ordinary manner in order to ascertain what portion of a revolution in addition to the three whole revolutions is required, and the stop *q* is set upon the disk *n'* by means of the graduations marked thereon, so that the

actual stopping part will bring the zero line to coincide with that graduation which corresponds to the fraction of a circle beyond the whole revolutions through which the handle *f* is to move. This having been done, the clamp *k* is tightened and the handle *f* is turned the required number of whole revolutions, the stop *q*, as before, being turned out of the way upon its center; but when these whole revolutions have been made the trigger *t'* is allowed to arrive in contact with the stop *q*, and then the shaft *b* will have been turned through a determined space. When this has been done the clamp *g* is loosened and the handle *f* is turned

in the reverse direction back to its notch *w*, and the same operations are repeated, the said notch always being the starting-point, and, therefore, in this apparatus there is one notch only, the 5 finishing points for parts of a circle being an adjustable stop.

In order to prevent any undue motion of the worm *c* a binding-screw, as at *x*, may be adapted and tightened between each working of the 10 handle *f*.

My invention is adapted to be applied to a variety of purposes. It can be used for giving intermittent motion to the pattern of a molding-machine of that class in which a segmental 15 pattern is used and which is carried by a radial arm, as is well known, then the said radial arm will be connected to the wheel *d*, and the segmental pattern will be caused to move at intervals through the necessary spaces for molding 20 successive teeth of wheels. In like manner the wheel *d* may give motion to the mold-box instead of to the pattern, such motion of the mold-box being well known.

In latches for cutting wheels or setting out, 25 the wheel *d* may be placed behind the face-plate, and after the same manner my inven-

tion may be adapted generally to machines for cutting, marking, or setting out divisions of circles; but none of such arrangements constitute any part of my invention. 30

In marking or setting out divisions in straight lines, as in the case of rules, the worm or screw *c* may be continued for the necessary length, and constitute the ordinary screw for traversing the cutting or marking tool. 35

Having thus fully described my invention, I claim as new and desire to secure by Letters Patent—

In apparatus for setting out, cutting, or working divisions on circular or straight lines, the 40 handle *f* provided with trigger *t* *t'*, clamp *i* *g*, graduated disk *n* *n'*, provided with groove *p* and notch *w*, and the stop *q*, combined together on shaft *a*, substantially as shown and described for operation as specified.

JAMES C. SCOTT.
